UNITED STATES PATENT OFFICE.

JOHN LANE, OF HYDE PARK, ASSIGNOR TO THE HAPGOOD PLOW COMPANY, OF ALTON, ILLINOIS.

LISTING-PLOW.

SPECIFICATION forming part of Letters Patent No. 250,152, dated November 29, 1881.

Application filed July 12, 1881. (No model.)

To all whom it may concern:

Be it known that I, JOHN LANE, of Hyde Park, in the county of Cook and State of Illinois, have invented a new and useful Improvement 5 in Listing-Plows, which improvement is fully set forth in the following specification and accompanying drawings.

My invention relates to improvements in the construction of "listing-plows;" and the object of my invention is to simplify and cheapen the construction, and to produce a more solid and light-weight foundation than heretofore on which to build the plow.

My invention consists in a bent plate of 15 flanges with perforations, in combination with a center bar and bent plow-beam, and with a listing-plowshare having wings extending obliquely both right and left, and with two mold-boards, and bolts uniting the share and both 20 mold-boards to the flanges, all as hereinafter shown.

Figure 1 is a vertical sectional view of a listing-plow, showing my improvements. Fig. 2 is a top sectional view of same. Fig. 3 is a 25 side elevation of the bent plate A and center bar, B, showing the flange a. Fig. 4 is a top view of the bent plate A and the bent bar B, showing how the flanges a and b are arranged. Fig. 5 is a cross-section taken on the dotted 30 line x x in Figs. 4 and 3.

A is the bent plate, consisting of a plate of iron or steel of the proper thickness and shape to form the two flanges a and b, and which I unite to the forward end of the center bar, B, preferably by welding, as shown in the drawings. The flanges a and b are bent drooping and formed to fit the under side of the mold-boards and share, and each flange has two perforations, c and h in the flange a, and d and

g in the flange b, by which the wings y and z 40 of the share S and the mold-boards m and n are united to the flanges with bolts, as shown in Fig. 1. There is a perforation, k, in the forward end of the plate A, which I sometimes use when making extra-strong plows. 45

S is the well known listing-plowshare, having the wings y and z extending obliquely both right and left from the point, and the wing y is united to the flange a with a bolt at h, and the wing z is united to the flange b with a bolt 50 at g, and the mold-board m is united to the flange a with a bolt at e, and the mold-board n is united to the flange b with a bolt at d, as shown in Fig. 2, by which the share, with its wings, and both mold-boards are held rigidly 55 together on the bent plate A; and A' is an ordinary bent plow-beam, having its foot end united to the center bar, and having side brackets, r r, supporting the top of the mold-boards, as shown in Figs. 2 and 1; and drill-teeth or 60 subsoil-blades may be attached, as shown in Figs. 1 and 2.

The bent plate A may be united to the center bar with bolts or rivets instead of welded thereto, and the bolt at k may or may not be 65 used, as desired.

Having thus set forth my invention, I claim—
In a listing-plow, the combination of the bent plate A, forming flanges a and b, perforated, as shown, with the center bar, B, bent plow-beam A', share S, having wings y and z, and the mold-boards m and n, substantially as and for the purpose set forth. 70

JOHN LANE.
